UNITED STATES PATENT OFFICE.

BENJAMIN F. RIX, OF KALAMAZOO, MICHIGAN.

SULKY-HARROW.

SPECIFICATION forming part of Letters Patent No. 267,718, dated November 21, 1882.

Application filed December 6, 1881. (No model.)

To all whom it may concern:

Be it known that I, BENJAMIN F. RIX, a citizen of the United States, residing at Kalamazoo, county of Kalamazoo, State of Michigan, have invented a new and useful Sulky-Harrow, of which the following is a specification.

My invention relates to that class of sulky-harrows which are provided with share-beams located beneath the wheel-frame in a manner 10 to be raised and lowered by lifting devices connected with said wheel-frame; and it has for its object certain improvements set forth in the following description and claims. The style of wheel-frame preferred by me as being especially adapted for use with the independent share-beams shown is provided with duplex side beams, between which the wheels are located.

In the drawings forming a part of this specification, Figure 1 is a side elevation of the harrow, looking from a point at the right-hand end of the share-beams; Fig. 2, top view of harrow complete; Fig. 3, rear view, showing the truss-brace of wheel-frame; Fig. 4, detached portion of Fig. 1; Fig. 5, the lever-wheel in Fig. 1 enlarged; Figs. 6 and 7, detached portions, showing changes in the pitch of the shares; Fig. 8, cross-section of the wheel-supporting beams on dotted line $\alpha\alpha$ in Fig. 2; Fig. 9, detached portion of Fig. 1, showing the operation of the lifting-lever; and Fig. 10 is an enlarged top view of the adjusting-casting in Figs. 6 and 7.

In the use of a wheel-frame having duplex side beams, B B, supporting the wheels H H, which are provided with the short axles $a' a'$, I form it rectangular, with end beams, D D', and a centrally-located cross-beam, N; but to obviate danger of the frame warping or 35 beams D D' springing I provide said beams with a truss-brace, S, secured to them and crossing beam N, with which it is also connected, as shown in Fig. 3. With this frame I connect the independent share-beams $\alpha\alpha$ in 40 two sets by means of the shaft-rods $c c$, pivotally connected with beams N, D', and B B. The rear share-beams, $\alpha\alpha$, are longer than those between the wheels H H, in order that shares may be located in the rear of said wheels 45 at $o o$. By this means a wider strip of land may be harrowed with less distance between wheels H H. The pivoted draft-bars $c c$ are connected with beams $a a$ by means of the adjusting-castings $e e$, pivot-bolt e' , and adjust-

ing-bolts e'' , Fig. 10. The pitch of the share 55 is thus readily controlled by locating bolt e'' in different perforations in the end of casting e , Figs. 6 and 7. Chains $n n$, with handles $r r$, are connected with the independent share-beams, and pass through staples driven 60 into the beams of the frame. By this means the share-beams may not only be raised in unison, as hereinafter explained, but by raising up the handles $r r$ they may be raised independently of each other. Between the duplex beams F F, located across the wheel-frame, I pivot the lever-wheel d and pulleys $i i$. Chains $y y'$ are secured to the front and 65 rear share-beams, pass over pulleys $i i$, and are secured to wheel d , as shown in Fig. 5. 70 Chain y' is secured to the center beam, a , and connected directly with wheel d , Figs. 1 and 5. Thus a person sitting in the driver's seat can readily operate either the lifting-lever, raising all the share-beams at once, as shown 75 in Fig. 9, or the handles r , raising a single beam, a , as shown in Fig. 4.

To obviate danger of the share-beams swaying laterally, owing to their being disconnected from each other, and not being located 80 in a regular frame, I employ braces $t t$, connecting with castings e by means of bolts e' , and pivoted at their upper ends to the frame.

I am aware that wheel-harrows have heretofore been provided with means for raising 85 and lowering independent sections of the share-supports separately and together. Hence I do not claim such features, broadly; but

What I claim is—

1. In a wheel-harrow, the combination, with 90 the independent share-beams, the pivoted draft-rods adjustably connected thereto, and the lateral braces, of the lever-wheel and pulleys, the lifting-chains attached to said lever-wheel, and the independent lifting-chains, 95 whereby the share-beams may be raised and lowered independently or in unison.

2. In a wheel-harrow, the independent share-beams and the pivoted draft-rods adjustably connected with said beams, in combination 100 with the lever-wheel, the pulleys, the lifting-chains attached to said lever-wheel, and the independent lifting-chains, for the objects specified.

BENJAMIN F. RIX.
